STEPHEN R. COLEMAN, OF OKLAHOMA, OKLAHOMA, ASSIGNOR TO WESTERN BANK SUPPLY COMPANY, OF OKLAHOMA, OKLAHOMA, A CORPORATION OF OKLAHOMA.

LEDGER-BINDER TRAY.

1,290,512.

Specification of Letters Patent.

Patented Jan. 7, 1919.

Application filed April 18, 1918. Serial No. 229,304.

To all whom it may concern:

Be it known that I, STEPHEN R. COLEMAN, a citizen of the United States, residing at Oklahoma, in the county of Oklahoma and 5 State of Oklahoma, have invented new and useful Improvements in Ledger-Binder Trays, of which the following is a specification.

This invention relates to a ledger binder 10 tray designed for use in place of loose leaf ledger binders for binding loose leaf ledger sheets.

The primary object of the invention is to 15 provide a binder tray which affords greater ease and convenience, in binding, removing, adjusting and otherwise handling the sheets, and especially in using the sheets in conjunction with ledger posting machines, over 20 binders of ordinary construction.

Another object of the invention is to provide a binder tray which will accommodate 25 sheets of different sizes, and which admits of the more ready, convenient and accurate placing of the sheets in position, as well as the lateral adjustment of the sheets to certain 30 positions, as, for instance, the extension of the sheets to the left to indicate over-drafts, etc.

Still another object of the invention is to 35 provide a binder tray in which the followers are constructed to bring a bearing pressure upon the centers of the sheets, thereby firmly clamping the sheets and holding them in a compact manner.

Still another object of the invention is to 40 provide a binder tray of great storage capacity, and embodying in its construction side pieces which are adjustable laterally to suit different widths of ledger sheets, to serve as guides to facilitate the insertion of the sheets, and to serve as stops to permit lateral adjustment or extension of the sheets for specified purposes.

With these and other objects in view, the 45 invention consists of the features of construction, combination and arrangement of parts, hereinafter fully described and claimed, reference being had to the accompanying drawing, in which:—

50 Figure 1 is a central vertical longitudinal section through the binder tray.

Fig. 2 is a top plan view of the tray.

Fig. 3 is a vertical transverse section on line 3—3 of Fig. 2.

Fig. 4 is a perspective view of one of 55 the retaining clips.

The binder frame comprises a tray of rectangular or oblong rectangular form and consisting of a bottom wall 1 and short front and rear end walls 2 and 3 rising therefrom. The bottom wall 1 forms a support on which the bottom edges of the stack of ledger sheets are designed to rest, and said wall is formed in its upper face with a central longitudinally extending groove 4 in which is disposed a follower actuating shaft 5 having oppositely threaded end portions 6 and 7, one of said end portions having a right hand thread and the other a left hand thread. At its center the shaft 70 is provided with a smooth-surfaced portion 8 journaled in a central bearing 9 secured within the groove 4, and at its rear end the shaft is formed with a smooth-surfaced portion or journal 10 which is fitted for rotation in a bearing recess 11 in the rear end wall 3. The forward end of the shaft terminates in a smooth-surfaced portion or journal 12, fitted for rotation in a bearing member 13 secured within the groove 4, and an angular portion 14 projecting into an opening 15 formed in the front end wall 2. This opening 15 is adapted for the reception of an operating handle or key having an angular socket to engage the angular end 14 of the shaft, whereby said shaft may be rotated for the purpose of adjusting the followers.

The ledger sheets resting upon the bottom wall 1 are adapted to be clamped and held between a pair of follower members 16 and 17, each comprising a vertically disposed follower board or plate 18, of suitable size and shape, but preferably of oblong or oblong rectangular form, and having at its 90 side edges flanges 19 projecting in the reverse direction to its clamping face and in parallel relation to each other. The clamping plate 18 is mounted upon a carrier bracket consisting of a horizontal transverse base piece 20 having at its ends upright arms 21. The arms 21 lie in rear of the clamping plate 18 and have forwardly curved or offset upper ends 22 provided with forwardly projecting rounded lugs or 95 ears 23 and upper rear stop shoulders 24, the lugs 23 being apertured to receive pivot pins or rivets 25 on which the flanges 19

of the clamping plate 18 are pivotally mounted, substantially in line with the horizontal transverse center of said clamping plate, or at a point about midway of the 5 height thereof. By this construction the clamping members or plates 18 are pivotally mounted to tilt or swing upon the bracket arms so as to adjust themselves to properly accommodate the interposed stack of ledger 10 sheets and to permit the clamping plates to assume a substantially vertical clamping position. The clamping plates are thus adapted to exert their major clamping pressure centrally of the sheets, instead of at or near 15 the bottom edges thereof, whereby the sheets will be compactly held and more securely clamped against liability of displacement. The base pieces 20 of the carrier brackets are provided with guide members 26 movable in the groove 4 and having threaded 20 openings for the passage of and for engagement with the respective threaded portions 6 and 7 of the shaft, said guide members thus serving as nuts whereby when the 25 shaft is turned in one direction the followers will be moved toward one another and when the shaft is moved in the reverse direction the followers will be spread apart or moved away from one another, such 30 adjustments adapting the sheets to be clamped and released in an obvious manner.

Secured to the inner faces of the upright end walls 2 and 3 by screws 27 and spacing washers 28 are horizontal transverse bracket 35 plates 29 provided with longitudinally extending guide slots 30. These bracket plates are designed for adjustably supporting a pair of sheet retaining rods 31 extending longitudinally above the bottom wall 1 on 40 opposite sides of the groove 4, said rods engaging the usual notches in the lower edges of the sheets. The front and rear ends of the rods are adjustably supported in position upon the bracket plates 29 by U-shaped 45 spring metal clips 32, which are arranged to straddle and slidably engage the bracket plates. The leaves of each of these U-shaped clips are formed with registering openings 33 to receive the ends of the rods, which 50 also pass through the slots 30 in the bracket plates 29, whereby the rods are connected with the clips and slidably mounted upon the bracket plates for adjustment, while they are held from casual displacement. 55 The leaves of the clips 32, by their spring action, engage the sides of the bracket plates 29 with sufficient friction to maintain them in adjusted position, while permitting them to be slidably adjusted whenever it is desired 60 to space the rods 31 a greater or less distance apart, to register with the notches in the lower edges of ledger sheets of different widths, the binder thus being adapted to receive and hold ledger sheets of different 65 widths or sizes within any desired range.

The sheets supported by the binder tray are held from lateral displacement by duplicate side pieces 34 and 35, each comprising a bail-shaped rod or wire. The body portion of each side piece extends longitudinally and horizontally above the bottom wall 1 and between the end walls 2 and 3 and has its downturned end portions 36 terminating in journals 37 and 38 which are respectively mounted in a bearing opening 39 in the front wall 2 and a bearing recess 40 in the rear wall 3, thus mounting the side pieces 34 and 35 to tilt or swing laterally in an inward or outward direction. The journal 37 of each side piece is elongated 70 and extended outwardly through the opening 29 and threaded to receive an internally threaded thumb button or nut 41 which may be turned up to bear against the wall 2 and thus frictionally clamp the side piece in any 75 position of adjustment. The two side pieces 34 and 35 may be disposed in a normally vertical position to retain and hold from lateral displacement sheets of a given width, may be tilted inwardly to varying degrees 80 to decrease the distance between them for retaining sheets of narrower width, and may be tilted outwardly to retain sheets of a greater width. In inserting sheets within 85 the binder the two side pieces 34 and 35 may 90 be tilted outwardly to form inclined guides, whereby the sheets may be more easily and conveniently inserted in position, and the right hand guide 35 may be adjusted to any 95 prescribed position for use as an abutment 100 or guiding edge against which the right hand edges of the sheets may be brought to bear as they are inserted to bring the notches in the lower edges of the sheets into exact 105 register with the rods 31, thus adapting the sheets to be applied very rapidly and with great accuracy, whereby such work may be facilitated. The side piece 34 may be tilted 110 outwardly to any extent to allow any of those sheets showing over drafts, or which 115 otherwise require special attention, to be lifted from engagement with the rods 31 and extended or drawn out so as to project at the left of the stack, in order that such 120 sheets may be separated from the body of the stack to receive special attention in posting or other work.

The binder as thus constructed may be supported upon a suitable stand and is especially designed for binding ledger sheets and 125 for use in connection with ledger posting machines, whereby a large number of ledger sheets may be bound in a stack and disposed in such manner as to be readily, quickly and conveniently removed or adjusted and replaced, as to afford increased advantages in 130 posting and other similar work, while at the same time giving also increased capacity over ordinary loose leaf binders. It will, of course, be obvious that the tray may be made 135

of any given size and by reason of its construction is adapted to hold, in a compact form, a much greater number of sheets than an ordinary type of loose leaf binder, and 5 that, as the followers are adapted to clamp the sheets at a central point, the sheets will be more compactly held and, when the followers are retracted, may be removed or replaced without difficulty or inconvenience. 10 Furthermore, it is evident that by the provision of the adjustable side pieces 34 and 35 greater convenience is afforded in enabling the sheets to be rapidly inserted with great accuracy, removed with freedom, and ad- 15 justed or extended laterally to bring certain sheets to a position for special attention, making the device especially advantageous in binding a large number of ledger sheets together and in facilitating the operation of 20 posting and other similar work.

It is to be understood that while it is desirable to have both side pieces 34 and 35 adjustable as described, I do not limit the invention thereto, as one of the side pieces 25 may be made rigid and the other adjustable, or both made adjustable, within the scope of the invention as defined in the appended claims.

Having thus fully described my invention, 30 I claim:—

1. In a binder of the character described, the combination of a binder frame, a follower support having uprights provided with forwardly offset portions, and a clamping member pivoted to said offset portions of the uprights substantially midway of the height of the member so as to bear upon the center 35 of a sheet to be clamped.

2. In a binder of the character described, 40 the combination of a binder frame, a follower support having forwardly offset portions, and a follower clamp having rearwardly extending flanges pivoted to said offset portions of the uprights at a point about midway of the height of the follower clamp, so as to adapt said follower clamp to bear 45 upon the center of a sheet to be clamped.

3. In a binder of the character described, 50 the combination of a binder frame, a fol- 55 lower support having upright arms provided at their upper ends with forwardly offset portions lying in advance of the vertical plane thereof, and a follower clamp having rearward extensions pivoted to said offset portions of the uprights at a point substantially midway of the height of the follower clamp so as to adapt said follower clamp to bear upon the center of a sheet to be clamped.

60 4. In a binder of the character described, the combination of a binder frame, follower supports adjustably mounted on the binder frame, each of said supports having a pair

of upright arms provided with forwardly offset portions, means for adjusting said fol- 65 lower supports toward or from each other, and follower clamps having rearward extensions pivoted to the offset portions of the follower supports approximately midway of the height of said follower clamps. 70

5. In a binder of the character described, the combination of a binder frame, slotted bracket plates at the ends of the binder frame, spring clips slidably embracing said bracket plates, and sheet retaining rods car- 75 ried by said clips.

6. In a binder of the character described, the combination of a binder frame, slotted bracket plates at the ends of the binder frame, U-shaped spring clips slidably embr- 80 acing said bracket plates and having registering openings in the leaves thereof, and sheet retaining rods having their end portions fitted in the openings of the clips and extending through the slots of the bracket 85 plates.

7. In a binder of the character described, the combination of a binder frame, sheet retaining and clamping means upon the binder frame, and a laterally adjustable side piece 90 at a side of the binder frame.

8. In a binder of the character described, the combination of a binder frame, sheet retaining and clamping means upon the binder frame, a laterally swinging or tilting side 95 piece at a side of the binder frame, and means for holding said side piece in adjusted position.

9. In a binder of the character described, the combination of a binder frame, sheet 100 retaining and clamping means upon the binder frame, and laterally adjustable side pieces at the sides of the binder frame.

10. In a binder of the character described, the combination of a binder frame, sheet re- 105 taining and clamping means upon the binder frame, and laterally swinging or tilting side pieces at the opposite sides of the binder frame.

11. In a binder of the character described, the combination of a binder frame, sheet re- 110 taining and binding means upon the binder frame, laterally tilting or swinging side pieces at the sides of the binder frame, and means for securing the same in adjusted po- 115 sition.

12. A ledger sheet binder comprising a tray-like frame consisting of a base and front and rear end pieces, sheet binding and clamping means supported by the binder 120 frame, adjustable side pieces extending along the sides of the binder frame, and means for securing said side pieces in adjusted position.

In testimony whereof I affix my signature. 125
STEPHEN R. COLEMAN.
